UNITED STATES PATENT OFFICE.

CHARLES E. MORRIS, OF LEAVENWORTH, KANSAS, ASSIGNOR TO CHARLES W. PARKER,
OF LEAVENWORTH, KANSAS.

REVOLVING TEETER.

1,261,149.

Specification of Letters Patent.

Patented Apr. 2, 1918.

Application filed March 20, 1916. Serial No. 85,345.

To all whom it may concern:

Be it known that I, CHARLES E. MORRIS, a citizen of the United States, residing at Leavenworth, in the county of Leavenworth 5 and State of Kansas, have invented a certain new and useful Improvement in Revolving Teeters, of which the following is a specification.

My invention relates to improvements in 10 revolving teeters.

The object of my invention is to provide a teeter of novel construction, which is strong and durable, which may be economically manufactured, and in which the oscillations 15 of the teeter member effects its rotation on a vertical axis.

A further object of my invention is to provide novel means by which the persons carried by the teeter member may effect its 20 oscillation without having to strike the ground with their feet.

Still another object of my invention is to provide novel means for normally forcing the oscillatory teeter member to the horizontal 25 position.

Another object of my invention is to provide novel means for adjustably balancing the oscillatory teeter member so as to compensate for the difference in weight of the 30 persons carried thereby.

Other novel features of my invention are hereinafter fully described and claimed.

In the accompanying drawings, which 35 illustrate the preferred embodiment of my invention,

Figure 1 is a side elevation of my improved teeter.

Fig. 2 is a top view of the same.

Fig. 3 is an enlarged vertical sectional 40 view of a central portion of my improved teeter, taken on the line 3—3 of Fig. 4.

Fig. 4 is an enlarged view, partly in side elevation and partly in vertical section of the central portion of my improved teeter.

Fig. 5 is a horizontal sectional view on the plane of the line 5—5 of Fig. 3, some of the parts being omitted and some broken away.

Fig. 6 is a cross section on the line 6—6 of 50 Fig. 5.

Similar reference characters designate similar parts in the different views.

My improved teeter is provided with a support comprising preferably a stationary portion and a head revoluble thereon on a vertical

axis. The stationary portion comprises, preferably, a stationary head 1 which is mounted upon the upper end of a standard 2, preferably tubular and having its lower end rigidly secured to and supported by a horizontal base 3 of any suitable form and construction. 60

Inclined braces 4 have their upper ends preferably detachably secured to the head 1 and having their lower ends detachably secured to the base 3. Rigidly and centrally secured at its lower end in the head 1 is a vertical spindle 5 on which is revolubly mounted a revoluble head 6, which is preferably supported upon a series of balls 7, 70 which are disposed in a circular ball race provided therefor in the upper side of the stationary head 1 and concentric with the spindle 5, as shown in Fig. 3.

Opposite sides of the revoluble head 6 are 75 provided with trunnions 8, on which are pivotally mounted respectively two bearings 9 which are respectively secured to two horizontal parallel angle bars 10 which form the side members of a teeter member. 80

Secured respectively to the middle portions of the bars 10 are two A-shaped standards 11 on the upper ends of which are respectively mounted two truss rods 12, the outer ends of which are respectively secured 85 to the bars 10 adjacent to the ends thereof.

Mounted respectively on the outer ends of the bars 10 are two seats 13, which are adapted to be respectively occupied by the persons who are to operate the teeter. 90

For normally forcing the teeter member to the horizontal position, there are provided two coil springs 14, the inner ends of which are secured respectively to opposite ends of an eye bolt 15, Fig. 4, which is secured to and 95 extends through the revolving head 6 adjacent to the upper end thereof.

The outer ends of the springs 14 are respectively secured to opposite ends of a horizontal rectangular frame 16, the longitudinal 100 sides of which are respectively secured to the standards 11 adjacent to the upper ends thereof. The longitudinal sides of the frame 16 are disposed parallel to the bars 10.

For adjustably balancing the oscillatory 105 teeter member so as to compensate for the difference in weight of the persons occupying the seats 13, there are preferably provided two counter-balancing weights 17 respectively longitudinally slidably on the 110

bars 10 at opposite sides of the horizontal axis of the oscillatory teeter member. Opposite edges of each weight 17 are longitudinally grooved to respectively receive the 5 horizontal flanges of the bars 10, Fig. 6. Each weight 17 is provided with two screw-threaded holes respectively intersecting said grooves and having mounted therein two set screws 18, which are adapted to respectively bear against the adjacent bars 10 for retaining the weights 17 in the positions to which they may be adjusted. By loosening the screws 18, the weights 17 may be slid to their proper positions and then retained 10 therein by tightening the set screws.

In order that the occupants of the seats 13 may oscillate the teeter member on the trunnions 8, there are provided two levers 19 which are respectively closely adjacent 20 to the seats 13 and which have their lower ends respectively pivoted to two transverse bars 20, which are secured at their opposite ends to the two bars 10 adjacent to the seats 13, see Fig. 2.

25 Respectively secured at their outer ends to the levers 19, are two rods 21, the inner ends of which are respectively secured to opposite ends of an eye bolt 22, Fig. 4, which extends through and is secured to the revolving head 6.

By grasping the upper ends of the levers 19 and alternately pulling and pushing thereupon, the occupants of the seats 13 may effect the oscillation of the teeter member.

30 In order that the teeter member when oscillated may be rotated on its vertical axis, the following described construction is preferably provided.

The upper side of the stationary head 1 35 is provided with an annular upwardly extending peripheral flange 23, Fig. 3, on which are circumferentially slidably mounted two inverted U-shaped clamping members 24, the inner arms of which are adapted 40 to lockingly clamp against the inner side of the annular flange 23. The outer arm of each clamping member 24 is provided with a slot 25, Fig. 4, through which extends a cam lever 26, which is pivoted by means of 45 a vertical pin 27 to the member 24 and the outer end of which is connected by means of an ordinary universal joint 28, of the ball and socket type, to the lower end of an inclined rod or link 29, the upper end of 50 which is connected by a universal joint 30 similar to the joint 28 to the adjacent bar 10 at one side of the horizontal axis of the oscillatory teeter member.

The joints 30 are located respectively at 55 opposite sides of the horizontal axis of the

teeter member, as are the clamping members 24.

The inner ends of the cam levers 26 are adapted to lockingly engage the outer side of the annular flange 23 when the outer 65 ends of said cam levers are swung toward the ends of the teeter member which are nearest thereto. When the levers are swung in the opposite direction, they will be released from the flange 23, thereby permitting 70 a sliding movement of the clamping members 24 on the flange 23 in a counter-clockwise direction, as viewed in Fig. 5.

When the teeter member is oscillated, the upper ends of the links or rods 29 will be 75 alternately moved upwardly and downwardly. Upon their upward movement, the rods 29 will swing the levers 26 respectively so as to release the levers from the flange 23, thereby permitting the rods or links 29 80 to slide the clamping members 24 forwardly in a counter-clockwise direction, as viewed in Fig. 5.

When the upper ends of the rods or links 29 move downwardly, they will swing the 85 levers 26, in a direction such that the levers will lockingly engage the annular flange 23, thereby holding the clamping members 24 from sliding on the flange 23 in a rearward or clock-wise direction, as viewed in 90 Fig. 5.

As the rods or links 29 move from the inclined position toward the horizontal, they will by bearing against the levers 26 effect a rotatory movement of the oscillatory teeter 95 member around the axis thereof. Thus, as the teeter member oscillates, it will also revolve and its revolving movement will cause a step by step advancement on the flange 23 of the clamping members 24.

I do not limit my invention to the structure shown and described, as modifications, within the scope of the appended claim, may be made without departing from the spirit of my invention.

100 What I claim is:—

In a revolving teeter, a support having a vertical annular flange, a teeter member oscillatable on the support on a horizontal axis and rotatable on the support on a vertical axis, a clamping member slidable on the flange and adapted to be locked to one side of said flange, a lever pivoted to said clamping member and adapted to engage and clamp the opposite side of said flange, 110 and a link connecting the lever and the teeter member.

115 In testimony whereof I have signed my name to this specification.

CHARLES E. MORRIS.
